[57] **CLAIM**

The ornamental design for a cartridge for a hand-held electronic game, as shown and described.

DESCRIPTION

FIG. 1 is a top, front right side perspective view of a cartridge for hand held electronic game showing my new design;

FIG. 2 is a bottom, rear, left side perspective view thereof;

FIG. 3 is a top plan view thereof;

FIG. 4 is a bottom plan view thereof;

FIG. 5 is a rear elevational view thereof;

FIG. 6 is a front elevational view thereof;

FIG. 7 is a left side elevational view thereof;

FIG. 8 is a right side elevational view thereof;

FIG. 9 is a top, front, right side perspective view of a second embodiment of my design;

FIG. 10 is a bottom, rear, left side perspective view thereof;

FIG. 11 is a top, front, right side perspective view of a third embodiment of my design;

FIG. 12 is a bottom rear, left side perspective view thereof;

FIG. 13 is a top, front, right side perspective view of a fourth embodiment of my design;

FIG. 14 is a bottom, rear, left side perspective view thereof;

FIG. 15 is a top, front, right side perspective view of a fifth embodiment of my design;

FIG. 16 is a top, front, right side perspective view of a sixth embodiment of my design;

FIG. 17 is a top, front, right side perspective view of a seventh embodiment of my design;

FIG. 18 is a top, front, right side perspective view of an eighth embodiment of my design;

FIG. 19 is a top, front, right side perspective view of a ninth embodiment of my design;

FIG. 20 is a bottom, rear, left side perspective view thereof;

FIG. 21 is a top, front, right side perspective view of a tenth embodiment of my design;

FIG. 22 is a bottom, rear, left side perspective view thereof;

FIG. 23 is a top, front, right side perspective view of an eleventh embodiment of my design;

FIG. 24 is a bottom, rear, left side perspective view thereof;

FIG. 25 is a top, front, right side perspective view of a twelfth embodiment of my design;

The undisclosed end, side and bottom of FIGS. 15-18 and 25 are identical to that shown in FIG. 24 of the eleventh embodiment.

*Fig. 1**Fig. 2**Fig. 3**Fig. 4**Fig. 7**Fig. 5**Fig. 8**Fig. 6**Fig. 9**Fig. 10**Fig. 11**Fig. 12**Fig. 13**Fig. 14**Fig. 15**Fig. 16**Fig. 17**Fig. 18**Fig. 19**Fig. 21**Fig. 20**Fig. 22**Fig. 24*
